(57) **CLAIM**

The ornamental design for a display screen with virtual three-dimensional shoe icon or display system with virtual three-dimensional shoe icon as shown and described.

DESCRIPTION

FIG. 1 is a front view of a display screen with virtual three-dimensional shoe icon in which the icon is shown in a perspective orientation;

FIG. 2 is another front view thereof, showing a side orientation thereof;

FIG. 3 is another front view thereof, showing an opposite side orientation thereof;

FIG. 4 is another front view thereof, showing a front orientation thereof;

FIG. 5 is another front view thereof, showing a rear orientation thereof;

FIG. 6 is another front view thereof, showing a top orientation thereof;

FIG. 7 is a front view of a display system with virtual three-dimensional shoe icon shown in a perspective orientation, the virtual three-dimensional shoe icon being the same design as shown in the first embodiment of FIGS. 1-6; FIG. 8 is another front view thereof, showing a side orientation thereof;

FIG. 9 is another front view thereof, showing an opposite side orientation thereof;

FIG. 10 is another front view thereof, showing a front orientation thereof;

FIG. 11 is another front view thereof, showing a rear orientation thereof; and,

FIG. 12 is another front view thereof, showing a top orientation thereof.

The virtual three-dimensional shoe icon shown in FIGS. 1-6 and 7-12 is shown in various orientations to provide an understanding of the three-dimensional appearance of the design. The broken lines showing the unshaded regions represent the shoe icon outsole and shoe icon interior and form no part of the claimed design. In FIGS. 1-6, the outermost broken line represents a display screen which forms no part of the claimed design. In FIGS. 7-12, the outermost broken line represents a portion of a field of view for a visual display and forms no part of the claimed design.
